UNITED STATES PATENT OFFICE.

EDWIN F. GUTH, OF ST. LOUIS, MISSOURI.

DESIGN FOR AN ELECTRIC CHANDELIER.

41,378.

Specification for Design.

Patented May 16, 1911.

Application filed February 23, 1911. Serial No. 610,452. Term of patent 3½ years.

To all whom it may concern:

Be it known that I, EDWIN F. GUTH, a citizen of the United States, residing at St. Louis, Missouri, have invented a new, original, and ornamental Design for Electric Chandeliers, of which the following is a specification, reference being had to the accompanying drawing, forming part thereof.

Figure I is a side elevational view of my new design, assembled with other parts of a

chandelier, the latter being shown in dotted lines; Fig. II is a bottom plan view thereof.

I claim:

The ornamental design for an electric chandelier, as shown.

EDWIN F. GUTH.
